(No Model.)

J. KASCHENBACH.
BED.

No. 596,166.

Patented Dec. 28, 1897.

UNITED STATES PATENT OFFICE.

JOHN KASCHENBACH, OF WILKES-BARRE, PENNSYLVANIA.

BED.

SPECIFICATION forming part of Letters Patent No. 596,166, dated December 28, 1897.

Application filed May 19, 1897. Serial No. 637,247. (No model.)

To all whom it may concern:

Be it known that I, JOHN KASCHENBACH, of Wilkes-Barre, in the county of Luzerne and State of Pennsylvania, have invented certain new and useful Improvements in Beds; and I do hereby declare the following to be a full, clear, and exact description of the invention, such as will enable others skilled in the art to which it appertains to make and use the same.

- 10 My invention relates to an improvement in beds, and more particularly to couplings for metal bedsteads, the object of the invention being to so construct a coupling between the rails and posts of a bedstead that a wide or 15 extended bearing of one part relatively to the other can be had, whereby to insure the rigidity of the bedstead and avoid all possibility of the shaking of the same when in use, as well as danger of the coupling becoming loose. 20 A further object is to produce a coupling for metal beds which shall be simple in construction, comparatively cheap to manufacture, and which shall be effectual in all respects in the performance of its functions. 25 With these objects in view the invention consists in certain novel features of construction and combinations and arrangements of parts, as hereinafter set forth, and pointed out in the claim.

30 In the accompanying drawings, Figure 1 is a view illustrating my invention with the parts of the coupling separated. Fig. 2 is a view of the coupling with the parts united. Fig. 3 is a sectional view. Fig. 4 is an end view.

35 A represents the post of a metal bedstead, and B one of the rails.

The post A is provided at a suitable point between its ends with an elongated enlargement 1, having its diametrically opposite

40 faces flattened, as at 2, so as to form inclined shoulders 3, disposed practically at diametrically opposite sides of the enlargement 1.

The rail B is provided at its end with a yoke 4, which is preferably made semicircular, so

45 as to conform to the curvature of the face 5 of the enlargement 1 and lie closely against the same, thus forming a long bearing between

the rail and the post. The free ends of the arms of the yoke 4 are made internally with inclined shoulders 6, which when said yoke 50 is slid onto the enlargement 1 will engage the shoulders 3 thereon. The shoulders 3 and 6 being inclined, it is apparent that as the yoke is forced down it will be made to embrace the enlargement 1 and its internal face will 55 be drawn tightly against the curved face 5 of said enlargement.

Owing to the wide bearing between the rail and the post afforded by my improved coupling, the bedstead will be made rigid and not 60 liable to shake or become loose. My improved coupling also affords quick and easy means for connecting the parts of the bedstead in a tight and efficient manner.

My improvements are simple in construction, comparatively cheap to manufacture, and are effectual in every respect in the performance of their functions.

Slight changes might be made in the details of construction of my invention without departing from the spirit thereof or limiting its scope, and hence I do not wish to limit myself to the precise details herein set forth.

Having fully described my invention, what I claim as new, and desire to secure by Letters 75 Patent, is—

The combination with a post having a curved or cylindrical portion thereon, said curved or cylindrical portion flattened at opposite points and provided with inclined 80 shoulders adjacent to these flattened portions, of a yoke adapted to span this curved or cylindrical portion and provided with inclined shoulders which embrace the shoulders on the post whereby as weight is applied the bed 85 is drawn tighter and tighter together.

In testimony whereof I have signed this specification in the presence of two subscribing witnesses.

JOHN KASCHENBACH.

Witnesses:

M. H. MCANIFF,
JOHN A. MANGAN.
